ATTORNEY,

UNITED STATES PATENT OFFICE.

GEORGE W. MCGILL, OF NEW YORK, N. Y.

SUSPENSION DEVICE.

SPECIFICATION forming part of Letters Patent No. 392,519, dated November 6, 1888.

Application filed August 21, 1888. Serial No. 283,307. (No model.)

To all whom it may concern:

Be it known that I, GEORGE W. MCGILL, a citizen of the United States, residing at New York, in the county of New York and State of New York, have invented new and useful Improvements in Suspension Devices, of which the following is a specification.

My present invention relates to that class of suspension clips or devices used for suspending and exhibiting various articles of merchandise, and especially adapted for the suspension of curtains, such as portieres and others.

It is the purpose of my invention to simplify and improve the devices of this class by providing them with positive means of engagement with the articles suspended, and by combining with the support a guard by which the engaging pins are protected, so that strain on the pins is resisted.

My invention also has for its purpose to provide an improved construction of these devices, whereby the number of parts is lessened and the expense of manufacture reduced.

The invention consists in the novel features of construction and combinations of parts hereinafter fully set forth, and then definitely pointed out in the claims, the same being an improvement upon the invention contained in Letters Patent granted to me July 27, 1886, No. 346,300, for improvement in suspension devices.

In the accompanying drawings, Figure 1 is a sectional view on the line xx , Fig. 2. Fig. 3 is a front elevation of the device shown in Fig. 1. Fig. 3 is a detail elevation of the prepared blank from which the outer jaw with its guard-piece shown in Figs. 1 and 2 is made. Fig. 4 is a partial section on the line yy , Fig. 5, showing a modification. Fig. 5 is a front elevation of the device shown in Fig. 4. Fig. 6 is a detail of the guard-plate shown in Figs. 4 and 5. Fig. 7 is a front elevation showing another modification and illustrating a portion of a curtain suspended by the device. Fig. 8 is a detail showing the construction of the guard-plate in Fig. 7. Fig. 9 is a partial section on the line zz , Fig. 7. Fig. 10 is a transverse section on the line $z'z'$, and Fig. 11 is a view showing a modification of the device adapted to encircle a curtain-pole.

In the drawings, the reference-numerals 1 and 2 designate the clamping-jaws, which may be formed in two separate pieces united by a rivet, 3, as in Fig. 1, or of a single piece folded upon itself at the point 4, as in Fig. 4. Upon the extremity of the rearward jaw, 1, which is preferably widened or similarly enlarged at that point, I form or attach a stud or pin, 5, having suitable length and projecting outward at right angles with the clamping-face of the jaw. Within the similarly-shaped extremity of the other jaw, 2, is formed an aperture, 6, so shaped and situated as to receive and pass over the stud 5 when the jaws are pressed together, as shown in Figs. 4 and 9.

Below the clamping-face of the jaw 2, in which the opening 6 is formed, the jaw is prolonged to form a depending strip, as shown in Fig. 3. This strip is bent upward and arched or curved in front of the opening 6, thereby forming a semicircular guard, 7, which protects the protruding point of the stud 5 when the jaws are brought together, as shown in Figs. 1 and 2. This guard-strip may be formed of two strips, 8, integral with the jaw 2, but projecting laterally therefrom, as in Figs. 5 and 6, the curved jaw being formed by bending the lateral strips over toward each other until their ends meet, as in Fig. 5. I may also mount a series of studs, 5, upon one jaw and form a corresponding number of perforations, 6, in the other jaw, 2, as in Fig. 10. In this case the guard 7 would be formed, preferably, of the laterally-projecting strips 9, (shown in Fig. 8,) which afford perfect protection to the projecting points and prevent surrounding articles from catching thereon.

The construction and arrangement of the remaining parts shown are essentially the same as that shown in my patent already alluded to, and therefore require no specific description. Ears 10 are formed upon the jaw 1, projecting forward and beyond the jaw 2, and the hook 11, having a cam, 12, bearing upon the jaw 2, is pivotally mounted in said ears.

The jaw 1 may, if desired, be extended to engage with the hook, as shown in Fig. 9.

The studs or pins 5 may of course be formed or mounted upon either jaw. They form positive supports for the curtain or other article, which cannot be disengaged therefrom by any

strain on the studs. If such strain is applied, it is resisted by both jaws equally.

In Fig. 11 the plate comprising the jaw 1 is bent at its upper end into a ring, as at 13, to encircle and slide upon a curtain-pole.

By this invention all possibility of accidental detachment by reason of the article slipping by its own weight between the clamping-faces of the jaws or being drawn therefrom is wholly avoided, and the device is rendered suitable for the suspension of any article whatever, without regard to its weight or the purpose to which it is to be put, or to the clamping-power of the jaws.

15 What I claim is—

1. The suspending device herein described, composed of the connected jaws, one having one or more pins or studs projecting therefrom and the other being provided with one or 20 more apertures to receive said stud, and a guard for the projecting point of said stud composed of a strip of metal integral with the jaw and bent around the front of the aperture therein, substantially as described.

25 2. In the suspension device, the combina-

tion, with the connected jaws, provided, respectively, with a stud or pin and an opening through which the stud or pin projects when the jaws are clamped, of a guard, 7, formed of an integral strip bent over the outer face of 30 the perforated jaw, substantially as described.

3. The combination, with the jaws 1 and 2, provided, respectively, with studs 5 and openings 6, arranged side by side, of the strips projecting from opposite sides of the jaw and 35 bent toward each other over the perforations, substantially as described.

4. The suspending device consisting of two clamping-jaws, one having a penetrating-pin and the other an orifice and a guard arched in 40 front of the orifice, one of the jaws extended at its upper end into a ring, substantially as described.

In testimony whereof I affix my signature in presence of two witnesses.

GEORGE W. MCGILL.
